DERRICK STRUCTURE

Paul R. Nagle, Oklahoma City, Okla.

Application December 5, 1941, Serial No. 421,821

2 Claims. (Cl. 189—15)

The present invention relates to derrick structures and, while in some respects of considerable utility in the field of derrick-like structures generally, more particularly relates or pertains to an improvement in derrick structures of the type widely used in the oil fields.

The typical oil field derrick comprises a platform which rests upon the surface of the ground and a steel or wooden structure based upon the platform and rising vertically above it for a substantial distance. In the general case, the superstructure includes corner posts or legs and interconnecting bracing members such as tie-rods and struts, these members functioning to unite all portions of the structure into a truss-like column well adapted to withstand wind forces and to support vertical loads. Erection of a derrick of this type has usually been accomplished by following the procedure universally used in the erection of ordinary building structures of other types, that is, by placing one building unit or member upon another until a structure of desired height is attained. Customarily, the derrick legs are formed in a plurality of individual sections, as are the struts and tie-rods, and brought to the erection site to be there assembled together, such assembly being a rather time-consuming operation and one which involves a very considerable element of danger. A very substantial number of oil field operatives are killed or injured each year in the erection of such derricks.

In accordance with the present invention an improved derrick structure is provided, and an improved method of erection, the major elements of the structure being assembled together in groups before being brought to the erection site and the several groups of members being there erected in a novel manner. Thus, in accordance with this invention, each of the derrick legs is extensible and contractible, comprising a plurality of telescoping tubes, and the use of bolts or other securing devices for attaching the various sections of the legs in end-to-end relationship as heretofore generally found necessary is avoided. Transportation of the derrick to the well site is facilitated, and the time necessarily consumed in the erection of the derrick in the field greatly reduced.

It has heretofore been appreciated that telescoping derrick legs might advantageously be employed but no satisfactory mechanism for or method of actually erecting such telescoping legs and securing them in operative position has up until this time been proposed. In accordance with my invention each telescopic leg is, as a step

preliminary to the actual erection of the derrick super-structure, pivotally mounted upon a pedestal which is in turn rigidly supported upon the derrick platform. Simple means is provided, as for instance a rope and winch, for effecting tilting movement of each derrick leg about its horizontal axis of pivotal support in order to swing the telescopic leg into operative position, and further means is provided to effect a connection between the lower end of the leg as erected and the derrick platform so that the leg is locked in its erected position and at the same time is so supported that its weight, and any vertical thrust which may subsequently be imposed upon it, is transmitted directly to the supporting platform instead of being transmitted to the platform through the pedestal. After the telescopic leg has been erected and secured in its operative position, its inner telescopic sections may be extended by any suitable means and the various necessary girts or struts and tie-rods are positioned. Placement of the bracing members, however, can be readily effected and the structure as a whole can be erected in much less time than heretofore, at less expense, and with a greatly reduced element of danger. Likewise, if it is desired to dismantle the derrick and transfer it to another position the dismantling operation is greatly facilitated by reason of its novel construction.

In the accompanying drawings one form of the derrick structure is illustrated, and will now be described in detail. It will be appreciated by those skilled in the art, however, that the embodiment of the invention shown and described is set forth by way of example only.

In the drawings:

Figure 1 is a side elevation of a derrick embodying the novel features of the invention, the derrick being shown in its erected or finished and operative position;

Figure 2 is a plan view of the derrick platform showing the derrick legs in the position which they occupy just prior to their movement into operative position;

Figure 3 is a section on line 3—3 of Figure 2;

Figure 4 is a section on line 4—4 of Figure 3;

Figure 5 is a view similar to Figure 3 being a partial section through the derrick platform adjacent one of the leg supporting pedestals, the leg however being shown in operative or erected position, and

Figure 6 is a section through the lower end of the outer tubular member of the telescopic leg, showing the means for locking the leg in oper-

ative position and transferring its weight to the platform.

The platform upon which the derrick super-structure is to rest is diagrammatically indicated at 10 in the drawings and it will be observed that this platform is square as is customary, although the invention is not limited to a derrick structure which includes a platform of any particular shape or outline. Likewise the platform may advantageously be fabricated in sections secured together instead of being fabricated at the site of the derrick of individual structural elements. At each corner of the derrick platform is positioned a pedestal 11 the base flange 11' of which is rigidly secured to the platform as by means of bolts 12. The pedestal 11 may be formed in any suitable way, advantageously being constructed, as shown in the drawings, of two upwardly extending angularly disposed and marginally interconnected webs 11'. Upon the upper end of the pedestal is rigidly secured a bracket 13 having spaced horizontally aligned bearings for a pin 14 which pin likewise projects through a cylindrical aperture in a bracket 15 rigidly secured to the derrick corner post or extensible leg indicated at 16.

Each derrick leg 16, of which there are four, comprises three telescoping tubular sections indicated at 16a, 16b and 16c, respectively, the two last mentioned sections being shown in Figures 2 and 3 to be telescoped within the first mentioned or major section 16a, save only for their protruding ends. As shown in Figure 2 the axis of each of the pivot pins 14 is disposed at right angles to the axes of the two adjacent pivot pins 14 and as a result each of the four legs 16 of the derrick is disposed at a right angle to each of the adjacent legs. Preferably the several legs are angularly disposed with respect to the platform edges, the longitudinal axis of each leg passing, when the leg is in horizontal position, through the vertical axis of the derrick (i. e. through a vertical line passing through the center of the derrick platform).

As shown in Figure 3 the derrick leg 16 is in a substantially horizontal position and when occupying such position it may be said to be in an intermediate stage of erection. When first positioned upon pedestal 11 the outer protruding end of the inner telescoping section 16c will normally rest upon the ground surface and the leg thus be disposed at a greater angle to the horizontal than it is shown to have in Figure 3. It is erected with the aid of erecting ropes or cables and a winch or windlass, an erecting rope being indicated at 20 in the drawings. One end of this rope is connected to an annular member or collar 21 rigidly clamped to the outer tubular section 16a of the derrick leg at or near that end of this section which will be lower-most after the leg has been locked in operative position. Rope 20 passes over a pulley or guide 22 supported upon a bracket 23 fixed to the associated pedestal 11 toward the base of such pedestal, and passes further over any other guide, such for instance, as 24, or guides, and thence to a rope winding means which is not illustrated. It will be readily perceived that when the erecting rope is tensioned the lower end of the leg 16 will be drawn downwardly and the entire leg rocked about the axis of the pivot 14. Eventually, the derrick leg will be drawn into the position in which it is illustrated in Figure 5, retaining or retarding ropes being employed to restrain the leg from tilting too far after its upper

end has passed over the axis of the pin 14 about which it is being tilted.

After having been erected to the position indicated in Figures 1 and 5 the derrick leg must be locked or secured in such position and to accomplish this the securing mechanism shown in Figure 6 is provided. This mechanism includes a socket member 30 rigidly secured to the platform 10, as by bolts 31, member 30 being provided with a spherical recess or socket 32 in its upper surface. A base casting projecting into and secured to the lower end of the outer section 16a of the tiltable leg is indicated at 33, this base casting being secured in position by bolts 34. It is provided with a threaded axial aperture to receive the exteriorly threaded jack screw 36. The outer end of jack screw 36 is enlarged and provided with cylindrical apertures 37 disposed at right angles to the axis of the screw, and a spherical part or knob 38 adapted to be received within the socket 32 on the socket member 30. A dust cap 39 covers the inner end of the jack screw-receiving recess, as shown, thus preventing the entrance of dust into the threaded recess 35 to cause wear of jack screw.

After a derrick leg has been moved to operative position, the associated jack screw 36 is revolved by bars or implements inserted into apertures 37 and the spherical protuberance 38 caused to move toward and into the socket 32 provided for its reception. When finally seated, the jack screw locks the associated derrick leg in its operative position and further than this it elevates the leg slightly so that the weight of the leg is not communicated to the platform through the brackets 13 and 15 and pin 14, but is transmitted directly from the bottom of the leg through the jack screw and socket member to the platform. The mechanism just described is not called upon to resist any substantial amount of lateral thrust after the derrick has been erected, the several legs being interconnected with each other by means of girt or strut members 40, tie-rods 41 and other securing and bracing members.

45 In the erection of the derrick the four telescoped corner posts or legs will first be erected by means of the erecting rope 20 and the several jack screws then operated to lock the telescoped legs in position. Following this, the tie-rods such as 41 connecting suitable brackets fixed to the outer leg section 16a may be positioned and girts or thrust rods such as 40 likewise positioned, thus laterally bracing the legs and preparing the way for further extension. The second section 16b of each leg or corner post may then be extended and locked in extended position by any suitable means, following which the second series of girts and tie-rods may be applied. This operation is again repeated with respect to the third or innermost leg section 16c and the derrick then provided with a cap structure and with its full complement of elements required in derrick operation, i. e., the derrickman's platform, suitable block and pulley devices etc., which are not illustrated.

60 After the derrick has remained as long as it is needed at any position or station, it may be disassembled by reversing the series of erecting operations just described and readily conveyed to some other point, to be again erected as quickly and conveniently as before.

Having thus described the invention, what is claimed as new and desired to be secured by Letters Patent is:

75 1. In a derrick, in combination, a platform, a

plurality of vertically elongated pedestals mounted on said platform, a derrick leg pivotally supported, at a point intermediate the ends thereof, on the upper end of each such pedestal so as to be movable from an inoperative position to a substantially vertical operative position, and means for securing each such leg in operative position, said means including a socket member on the platform and a socket engaging member adjustably mounted on the leg.

2. In a derrick, in combination, a platform, a plurality of vertically elongated pedestals mounted on said platform, a derrick leg pivotally sup-

ported at a point intermediate the ends thereof, on the upper end of each such pedestal so as to be movable from an inoperative position to a substantially vertical operative position, and means for securing each such leg in operative position, said means including a socket member on the platform, a socket-engaging member, and a member having threaded engagement with the leg so as to be adjustable axially of the leg, the said 10 socket-engaging member being mounted on said adjustable member.

PAUL R. NAGLE.
